UNITED STATES PATENT OFFICE.

JOSEPH A. SALZMAN, OF TOLEDO, IOWA.

SEAT-CONTROLLED CLOSET.

1,145,216.

Specification of Letters Patent.

Patented July 6, 1915.

Application filed March 18, 1913. Serial No. 755,214.

To all whom it may concern:

Be it known that I, JOSEPH A. SALZMAN, a citizen of the United States, residing at Toledo, in the county of Tama and State of Iowa, have invented new and useful Improvements in Seat-Controlled Closets, of which the following is a specification.

This invention relates generally to an improvement in toilets of that class known as seat controlled wherein the flushing operation is carried out by the weight of a person.

The main object of the present invention is the provision of a seat controlled toilet in which the flush tank is normally empty and is opened to the supply pipe by the weight of the person, the pressure of the water entering the supply tank serving to close the outlet between said tank and the bowl which outlet is opened upon the relief of the pressure through the automatic closing of the tank against the supply pipe by relieving the toilet of the weight of the person.

A further object of the invention is the utilization of an auxiliary feed pipe for directing the water supply into the bowl at times during the communication of the supply pipe and tank.

The invention in its preferred form of details will be described in the following specification, reference being had to the accompanying drawings, in which:—

Figure 1 is a perspective view illustrating the automatic toilet complete. Fig. 2 is an enlarged vertical sectional view through Fig. 1. Fig. 3 is a bottom plan of the seat. Fig. 4 is an enlarged broken elevation showing particularly the seat operation of the valve.

Referring particularly to the accompanying drawings, the improved automatic toilet includes a bowl 1 which, aside from the details of construction hereinafter described, may be of any preferred form of construction. For coöperation with the bowl I employ a tank 2 which although in its general form may be of any shape or size, though by reason of the peculiar construction of the operating parts it is to be understood that the flush tank is preferably of less capacity than the usual tank, thereby permitting it to be less conspicuous and more ornamental than usual.

The main or general supply pipe 3 leading from any suitable source of supply of water in the pressure rises to a position im-

mediately adjacent the bowl where it is preferably formed with an enlargement 4 from which extends an upright pipe 5 which at its juncture with the enlargement is formed to provide a valve seat 6. At a point above the valve seat the main feed pipe 7 is connected in open communication with the pipe 5, and between the pipe 7 and the valve seat 6 the pipe 5 is further provided with an auxiliary feed pipe 8 leading into the interior of the bowl at a point immediately above or in line with the trap therein, the inner end of the auxiliary feed pipe being preferably, though not necessarily, provided with a spray or cylinder 9.

A valve 10 is arranged in coöperation with the seat 6 having a flat or pressure face 11 next the water supply pipe 3, said valve, when open being arranged within the enlargement to permit the water to freely flow around the same. A stem 12 is connected to the valve 10, said stem extending through the pipe 5 and through an opening 13 formed in and through an offset 14 of the bowl proper, the upper end of the stem being provided with any suitable form of pressure head 15 for a purpose which will later appear. Above the feed pipe 7 the pipe 5 is interiorly closed against the upward passage of the water, being suitably packed to permit movement of the stem therethrough while preventing the passage of the water.

In the tank is arranged an approximately semi-cylindrical valve seat 16 communicating with the flush pipe 17 which leads from the tank and into the bowl in proper flushing relation to the latter, the usual guiding or spreading means for the water within the tank being employed to properly direct the flush. A stand pipe 18 is arranged within the tank, mounted if preferred in suitable guides to permit a vertical movement of said pipe, the lower end of the stand pipe being formed or provided with a valve 19 designed to coöperate with the seat 16. A spring 20 is arranged to normally maintain the stand pipe elevated, that is with the valve 19 off the seat 17, providing free communication between the flush pipe 17 and the tank. While preferring the spring 20 to normally maintain the valve 19 open it is obvious that other mechanical means may be employed to this end, and by the term spring I contemplate any equivalent structure which will normally maintain the valve open.

The feed pipe 7 leads to and through the

bottom of the tank and within the same to a point near the upper end being laterally projected and formed with a downturned delivery section 21 which opens at its free end 5 within the stand pipe and slightly spaced from the closed bottom thereof. A bell 23 is arranged to encircle the stand pipe, said bell having a diameter exceeding that of the stand pipe with its closed upper end embracing the delivery section of the feed pipe and its lower open end terminating some distance below the upper open end of the stand pipe. A pipe 24 is secured within the tank being closed at the lower end and opened at 10 the other end, said pipe being formed at its lower end with a comparatively minute pipe connection 25 which leads into the tank, as shown.

To provide for securing the toilet seat and 20 lid to the bowl in a manner to permit a proper operation of the seat in the toilet uses and prevent such operation of the seat when the lid in closed position, is used for an ordinary seat or support, I secure the 25 parts of the bowl by a peculiar hinge arrangement. In this arrangement, I secure uprights 26 to the bowl in the usual manner, and pivot the seat proper 27 thereto by a U-shaped member 28, the cross bar 29 of 30 which is rotatably connected to the seat by straps 29', and the arms 30 have lateral terminals 31 to seat in openings in the uprights. The rear end of the seat proper, which may have a slight projection, will 35 thus overlie the pressure head 15 of the stem 12 of the valve. The cover or lid proper, shown at 32, is hinged to the uprights above the connection of the seat thereto, the hinge connection 33 being of any appropriate type which will permanently support the rear end of the lid or cover to prevent pressure of the same on the seat, so that 40 when the seat and cover are in closed positions any pressure upon the lid will not 45 transmit movement to the seat to operate the valve.

In the use of the device, the weight of 50 the person will depress the seat with the effect to engage the pressure head 15 of the valve stem and open the valve. The water from the supply pipe 3 will now pass around the valve and to the feed pipe 7, a portion, however, of such water passing through the pipe 8 to wash the sides of the bowl. The 55 water leading through the supply pipe 7 is delivered into the stand pipe and by the initial pressure will seat the valve 19 against

its seat 16 and of course against the pressure of the spring 20. The water continuing to flow in the stand pipe will rise above the 60 same and flow downwardly between the stand pipe and below and into the tank, the downward movement of the water tending to further maintain the stand pipe in valve-seating position, as will be obvious. The 65 flow of the water continues during the occupancy of the seat or until the tank is completely filled. Prior to the complete filling of the tank the pipe 24 is filled. Upon relief of the pressure on the seat, the valve 10 70 closes and the pressure of the supply is cut off. The spring 20 regains control, the valve 19 is opened and the water in the tank flushes the bowl. After the flushing operation, which, owing to the size of the flush pipe, is 75 rapidly performed, the water remaining in the pipe 24 will trickle down into the bowl and supply the same with sufficient water to reestablish the trap.

It will thus be seen that the toilet is automatic in its operation, that when the same is not in use the tank is filled during the occupancy of the seat and emptied for the flushing operation immediately thereafter; that during the use of the toilet a stream is continually directed into the bowl and that the flushing operation of the bowl is not permitted until the relief of the tank from the pressure of the supply.

What is claimed is:

1. The combination with a bowl and flush tank, of a supply pipe, means normally closing said tank against the supply pipe, weight-operated means to establish communication between the supply pipe and 95 tank, and an auxiliary feed pipe establishing direct communication between the supply pipe and bowl subsequent to the operation of said means.

2. The combination with a bowl having a 100 trap and a flush tank, of a supply pipe, a valve normally closing the tank against said supply pipe, and an auxiliary feed pipe in communication with the supply pipe between the valve and tank, said auxiliary feed 105 pipe opening within the bowl above the trap.

In testimony whereof I affix my signature in presence of two witnesses.

JOSEPH A. SALZMAN.
